United States Patent Office.

JAMES E. GILLESPIE AND HORATIO B. WEAVER, OF HARTFORD, CONNECTICUT.

Letters Patent No. 101,255, dated March 29, 1870.

IMPROVEMENT IN WATER-WHEELS.

The Schedule referred to in these Letters Patent and making part of the same.

To all whom it may concern:

Be it known that we, JAMES E. GILLESPIE and HORATIO B. WEAVER, both of Hartford, in the county of Hartford, in the State of Connecticut, have invented a new and useful Improvement in Water-Wheels; and we do declare that the following is a full and exact description thereof, reference being had to the accompanying drawings and to the letters of reference marked thereon.

The nature of our invention consists in constructing a water-wheel in such a manner that, by certain appliances to the wheel, we are enabled to give a proper proportionate amount of power for the water used, let the amount of water be what it may.

To enable others skilled in the art to make and use our invention, we will proceed to describe its construction and operation.

The same letters refer to the same parts in all of the figures.

Figure 1 is an elevation of the wheel, and

Figure 2 is a section.

Figure 3 is a plan of the wheel, and

Figure 4 is a plan of the annular gate.

A is the shaft of the wheel, and has its bearings on the frame H.

B, the buckets or vanes of the wheel, and

C is a rim at the ends of the buckets or vanes, to give them proper support, and to serve the further purpose of making a joint where the wheel enters the side of the water-way F.

D is the body of the wheel to which the buckets or vanes B are permanently attached.

E is an annular gate that incloses the wheel, and is attached to it by means of the small ears on projections marked 1, 2, 3, &c., and is prevented from turning on the shaft by the presence of the spline or feather a, yet at the same time it is free to move upon the shaft in the direction of its length.

G is a groove in the hub of the annular gate E, to which may be applied any suitable mechanism to move the gate upon the shaft A.

By reference to the drawing it will be seen that the buckets or vanes B are on an exact circle, the radius of which is about three-fifths of the radius of the wheel, the center of the circle of the buckets or vanes B being in an exact line from the ends of the buckets or vanes to the center of the shaft.

The operation is as follows:

The water-way F being secured to the side of a flume or fore-bay, and secured to a suitable support, and the bearings of the shaft in position, then by any suitable means the annular gate is drawn upon the shaft and the water is free to flow out of the wheel, causing it to revolve in a direction opposite to the issuing water, but still in the direction of the flow of the stream in the water-way. The wheel may be placed near the top of the flume or fore-bay, and a draught tube used, if desired, or it may be placed at the bottom of the fall, as circumstances shall require.

What we claim as our invention, and desire to secure by Letters Patent, is—

1. A water-wheel having an annular gate, such as is hereinbefore described, applied in such a manner as to turn with the wheel, and at the same time be free to move upon the shaft of the wheel in the direction of its length.

2. The combination of the water-wheel, the annular gate E, and the projections marked 1, 2, 3, &c., the whole constructed substantially as described for the purpose set forth.

JAMES E. GILLESPIE.
HORATIO B. WEAVER.
